Primary Examiner — Sandra S Snapp*Assistant Examiner* — Katherine Glennon(57) **CLAIM**

The ornamental design for an alarm clock radio, as shown and described.

DESCRIPTION

FIG. 1 is a front elevation view of an alarm clock radio showing my new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a front perspective view thereof; and,

FIG. 8 is a rear perspective view thereof.

The broken lines shown in the drawings are for the purpose of illustrating portions of the alarm clock radio that form no part of the claimed design.

1 Claim, 8 Drawing Sheets(56)
